UNITED STATES PATENT OFFICE.

JANE GRAY STOKES, OF NEW YORK, N. Y.

DESIGN FOR A TOY MONKEY.

Application filed November 27, 1922. Serial No. 4,418. Term of patent 3½ years.

To all whom it may concern:

Be it known that I, JANE GRAY STOKES, a citizen of the United States, residing in the city of New York, borough of Manhattan, in the county of New York and State of New York, have invented a new, original, and ornamental Design for Toy Monkeys, of which the following is a specification, reference being had to the accompanying drawing, forming a part thereof, which is a front perspective of a toy monkey in sitting posture, showing my new design.

I claim:

The ornamental design for a toy monkey, substantially as shown.

JANE GRAY STOKES.
